UNITED STATES PATENT OFFICE

VINTON E. SISSON, OF CHICAGO, ILLINOIS, ASSIGNOR TO P. H. MURPHY COMPANY, OF NEW KENSINGTON, PENNSYLVANIA, A CORPORATION OF PENNSYLVANIA

CAR ROOF

Application filed July 23, 1927. Serial No. 207,923.

This invention relates to railway freight car roofs, and more particularly, to the all metal type of roof wherein relatively thick roof sheets span the distance between the 5 opposite side walls of the car and are preferably secured thereto and are so formed as to not only act as a roof in protecting the lading from the weather but also perform the functions of the usual car-lines, ridge 10 pole and purlins which in the ordinary car constitute the roof framing.

An object of the invention is to provide such a metallic roof having a longitudinal section with substantially convex portions 15 (forming arches or bridges) in one plane alternating with substantially concave portions (forming troughs or gutters) in a lower plane connected by substantially vertical web portions which arches and troughs 20 tend uninterruptedly between the web portions, so as to transmit loads imposed upon them to the webs.

Another object is to produce a roof comprising alternate convex and concave portions in different planes connected by substantially vertical web portions and having the distance between the several web portions and the thickness of the metal of the upper and lower portions so proportioned 30 and dimensioned that the neutral axis of the section is midway between the bounding planes of the section whereby the maximum strength of the steel roof is obtained.

Another object is to simplify the attachment of such a roof to the side walls of the car by gradually blending the respective convex and concave portions into straight portions adjacent the opposite side plates 35 of the car and furthermore so as to maintain the neutral axis midway between the bounding planes of the roof of any cross section between the opposite side plates of the car.

Another object is to produce a strong and 45 durable roof of simple construction which can be cheaply manufactured and easily assembled and which will permit the use of sheets of lighter gauge than those heretofore required for roofs of the all metal type, 50 thereby reducing the weight and cost of the

roof and at the same time greatly increasing its strength.

In the drawings:

Fig. 1 is a plan view of a part of a car with my improved roof applied thereon. 55

Fig. 2 is an enlarged section on line 2—2 of Fig. 1.

Fig. 3 is an enlarged section on line 3—3 of Fig. 1.

Figs. 4 to 9 inclusive show the preferred 60 contour of the longitudinal section of the roof made of one or more metallic sheets secured together at different places.

Figs. 10 and 11 show modified forms of 65 the longitudinal contour.

The roof sheets span the distance between the opposite side plates 2 and are preferably attached thereto in any convenient manner. The preferred longitudinal contour of the metallic roof is shown in Fig. 4 wherein 70 the portions 3 are arched or aped convexly (or upwardly) so as to form bridges to transmit any load imposed thereon to the substantially vertical web portions 4 and the portions 5 are depressed or aped concavely (or downwardly) to form gutters which deflect the rain, cinders, etc., away from the web portion. The convex and concave portions are positioned alternately with each other. The convexity of the convex portions and the concavity of the concave portions, respectively, extend uninterrupted between adjacent web portions. 75

The convex portion gradually merges into a straight portion 6 adjacent the side plate 85 and also the concave portion gradually merges into a straight portion 7 adjacent the side plate, which straight portions are preferably secured to the side plate, but the web 4 preferably remains constant in width 90 between the opposite side walls of the car.

The running board saddles (8, 9, 10) may be secured to any convenient part of the roof, as shown in Figs. 5, 6, and 8 respectively. 95

Fig. 5 shows the preferred construction wherein the convex roof sheets 12 are provided with depending flanges 13 at their opposite side margins and the concave roof sheets 14 are provided with upstanding 100

flanges 15 at their opposite side margins and the said depending flanges and upstanding flanges are secured together to form the web portions of the roof. The convex roof sheets 5 overlap the upstanding flanges of the concave sheets to form a shingle construction.

Fig. 6 shows a modified form wherein the upstanding flanges 20 of the concave sheets 21 are provided with outwardly projecting flanges 22 which are secured to the marginal portions of the convex sheets 23.

Fig. 7 shows a construction wherein each roof sheet is provided with a convex (30) and a concave portion (31) with an integral 15 web 32 therebetween and with an upstanding flange 33 at one side and a depending flange 34 at the other side of the roof sheet, the adjacent flanges of adjacent roof sheets secured together to form the web portion.

Fig. 8 shows a modification wherein each sheet is provided with a concave portion 40 and two web portions 41 and two semi-convex portions 42 with adjacent margins of adjacent sheets secured together at 43.

Fig. 9 shows a construction wherein each sheet is provided with a web portion 50 and a semi-concave portion 51 and semi-convex portion 52 and the adjacent margins of adjacent sheets secured together at 53 and 54.

Fig. 10 is a longitudinal cross section of the roof similar to that shown in Fig. 4 with the convex and concave portions each comprising two straight surfaces 60—61 angularly disposed to each other, while Fig. 11 35 shows a construction wherein the convex and concave portions each comprise three straight portions 62—63—64 angularly disposed to each other.

In the description and claims I have used 40 the phrase "convex portions" and "concave portions" but it is understood that the construction shown in Figs. 10 and 11 or the like come within the meaning of this phrase and the scope of the invention.

The convex portions 3 and the concave portions 5 are each preferably wider than 45 the distance 70 between parallel planes 71—72 bounding the outermost portions of the roof.

The accompanying drawings illustrate the preferred form of the invention, though it is to be understood that the invention is not limited to the exact details of construction shown and described, as it is obvious that 55 various modifications thereof within the scope of the claims will occur to persons skilled in the art.

I claim:

1. A metallic car roof comprising substantially convex roof sheets forming an arch between depending flanges at their opposite side margins, the convexity of said convex sheets extending uninterruptedly between the flanges thereon, said convex 60 sheets alternately disposed between substan-

tially concave roof sheets forming a trough between upstanding flanges at their opposite side margins, the concavity of said concave sheets extending uninterruptedly between the flanges thereon, the flanges of the convex sheets secured to the flanges of adjacent concave sheets. 70

2. A metallic car roof comprising substantially convex roof sheets forming an arch between depending flanges at their opposite side margins, the convexity of said convex sheets extending uninterruptedly between the flanges thereon, said convex sheets alternately disposed between substantially concave roof sheets forming a trough between upstanding flanges at their opposite side margins, the concavity of said concave sheets extending uninterruptedly between the flanges thereon, the flanges of the convex sheets overlapping and secured to the flanges 75 of adjacent concave sheets. 80
